(57) **CLAIM**

The ornamental design for a thermometer container, as shown and described.

DESCRIPTION

FIG. 1 is a top and front perspective view of a thermometer container showing our new design.

FIG. 2 is a bottom and rear perspective view thereof.

FIG. 3 is a bottom and front perspective view thereof.

FIG. 4 is a front elevational view thereof.

FIG. 5 is a right side elevational view thereof.

FIG. 6 is a left side elevational view thereof.

FIG. 7 is a rear elevational view thereof.

FIG. 8 is a top plan view thereof; and,

FIG. 9 is a bottom plan view thereof.

The dashed, broken lines in the figures depict unclaimed environment only and form no part of the claimed design.

1 Claim, 4 Drawing Sheets
